UNITED STATES PATENT OFFICE.

JOHN McLACHLAN, OF CHICAGO, ILLINOIS.

DITCHING-MACHINE.

SPECIFICATION forming part of Letters Patent No. 340,141, dated April 20, 1886.

Application filed November 2, 1883. Renewed March 24, 1886. Serial No. 196,423. (No model.)

To all whom it may concern:

Be it known that I, JOHN McLACHLAN, of Chicago, county of Cook, and State of Illinois, have invented certain new and useful Improvements in a Ditching-Machine, of which the following is a full, clear, and exact description, that will enable others to make and use the same, reference being had to the accompanying drawings, forming a part of this specification.

This invention relates to improvements in rotary ditching-machines; and it consists of a main rotating wheel formed of a number of excavating-buckets arranged radially, having a common hub, the earth removed dropping into the center, and from thence being carried outward and deposited on each side of the ditch by means of a spiral conveyer having a right and left pitch from the center.

It also consists of other features for operating and supporting the different parts of the mechanism, as will be hereinafter more fully set forth in detail, and pointed out in the claims.

Figure 1 is a side elevation of a machine embodying my improved features; Fig. 2, a plan view; Fig. 3, a central vertical transverse section. Fig. 4 is a central transverse section of the spiral conveyer and tubular shaft. Fig. 5 is an elevation showing the opposite side from that of Fig. 1; Fig. 6, a side elevation of the track, and Fig. 7 a plan of the same.

Referring to the drawings, A represents the frame-work supporting the different parts of the mechanism. The excavating-wheel B consists of a number of curved scoop-like buckets, B', having serrated cutting-edges, which are arranged radially with reference to each other and rotate in a common plane. The hub to which the buckets are attached consists of the two flange-disks A' A'', to the outer sides of which are in turn attached the annular bearing-boxes a a', which rotate on the annular bearing-collars a'' a'', which arrangement forms the required journal-bearings for the movement and support of the excavating-wheel, as shown in Fig. 3 of the drawings. The bearing-boxes a a' are of the angular form shown, the vertical part being secured to the disks carrying the buckets. The bearing-collars a'' a''' are rigidly secured to the sta-

tionary tubular shaft A³, inclosing the spiral conveyer A⁴. The top part of the tubular shaft or chamber inclosed by the excavating-buckets is provided with a rectangular opening, a⁴, through which the earth gravitates from the buckets into the conveyer, a space being provided between the base of each of the buckets which corresponds to said opening in the shaft inclosing the conveyer. The conveyer is pitched right and left from the center, so that the earth will be about equally divided and deposited on each side of the ditch and out of the way of the machine through the openings A⁵ A⁶ at each end of, and in the under side of the tubular conveyer-shaft. The excavating-buckets widen backward from the cutting-point, so that the earth will the more readily free itself, and are then slightly contracted toward the base to carry the earth more to the center of the opening communicating with the conveyer. The buckets may also be removably secured in position, so that larger or smaller buckets may be substituted, in accordance with the size of the ditch required. The main driving-shaft B² is located near the front end of the machine, the motive power employed being transmitted through the medium of the gear-wheel B³ and pinion B⁴, which may have any suitable connection with the source of power. The sprocket-wheel a⁵ is attached to the hub of the excavating-wheel, and the companion sprocket-wheel, a⁶, is placed on the main shaft, the two being connected by means of the link-belt b, by which means the necessary motion and power is transmitted to the excavating-wheel. The gear-wheel b' is placed on the opposite end of the hub and engages with the pinion b² on the inner end of the shaft b³, which is supported in suitable bearings. On the opposite end of this shaft is placed the gear-wheel b⁴, engaging with the pinion b⁵ on the conveyer-shaft b⁶, by which arrangement motion is imparted to the conveyer simultaneously with the movement of the excavating-wheel.

The track C (shown in Figs. 3 and 7 of the drawings) supports the whole weight of the machine when the same is in operation and moving forward, the track remaining stationary. One side of this track is provided with the rack-bar C', with which the gear-wheel C² engages. This gear-wheel is supported on the

inner end of the short shaft C³, while the ratchet-wheel C⁴ is placed on the outer end. The rocking arm C⁵ is also connected to the shaft C³ and projects upward therefrom, and has 5 one end of the eccentric-rod C⁶ pivoted thereto, as shown in Fig. 1. The opposite end of the rod C⁶ has the usual eccentric connection with the driving-shaft, which arrangement imparts the required movement to the machine 10 as it is intermittently fed forward by the feed-dog d, which engages with the ratchet-wheel C⁴, and is pivoted to the rocking eccentric arm C⁵. The pawl d', engaging with the same ratchet-wheel, locks the same against a back 15 movement. The track C is provided, near the front end, with the embedded friction-rollers d², and with the friction-rollers d³, placed at each side of and supported above the surface of the track by means the brackets d⁴. 20 These latter rollers rest upon a part of the base or bed timbers D D', supporting the framework of the machine proper, and serve to retain the track in proper relation to the same and ease the movement of the track as it is 25 adjusted to a new position.

The weight of the whole machine is supported on the track C when ditching; but when the machine has traveled the length of the rack-bar on the track the weight of the machine is shifted to the outside base-timbers, 30 D² D³, and the track moved forward another length. This alternate change is accomplished through the medium of the following mechanism: The two shafts D⁴ D⁵ are placed lengthwise of and near the top of the machine and 35 in a vertical line with the base-timbers D² D³. Each end of these shafts carry the bevel gear-wheels d⁵, which engage with the corresponding bevel-gears, d⁶, on the upper ends of the 40 vertical screw-shafts E, placed at each corner of the machine. A simultaneous movement is imparted to the horizontal shafts D⁴ D⁵ by the horizontal transverse shaft E', provided with the beveled gear-wheels E² on both ends, engaging with the companion wheels on the 45 screw-shafts E and the longitudinal shafts D⁴ D⁵. The lower ends of the vertical screw-shafts E are threaded and engage with the threaded nuts E³, secured to the under side of 50 the cross-timbers E⁴ E⁵. The lower ends of the brace-timbers e are secured to the timbers D² D³, while the upper ends incline toward each other, and are connected by the caps e', through which the vertical screw-shafts E pass. 55 The collars e² are rigidly secured to said shafts close to the under side of the caps e', and bear against the same when the screw-shafts are raised, thereby lifting the base-timbers D² D³ when necessary to transfer the weight of the 60 machine. The timbers D² D³ are forced down by means of the companion collars, e³, on the top of caps or cross-pieces e' when the shafts E are screwed down, the lower end of these screw-shafts having no bearing on the timbers 65 D² D³. Corresponding cross-timbers, F F', having connection with the vertical shafts E, pass underneath the longitudinal side timber

at the top of the frame-work supporting the mechanism. Now, by putting this system of connecting-shafts and bevel gear-wheels into motion, the machine is lifted at the four corners from the track and the weight transferred to the outside base-timbers, D² D³. The weight of the machine being raised from the track proper, permits the same to be moved forward 70 again to a new position; then, by rotating the system of shafts in the opposite direction the machine is lowered onto the track, and can then be fed forward another length of the track, and so on alternately as the work progresses. This construction and arrangement permits of the use of good broad track-timbers and of any desired length, so that the machine can be used in low and marshy places to a much better advantage than if supported and 75 propelled on wheels. The front end of the framework or machine is provided with the rotary harrow F², which serves the purpose of loosening up the soil, while the spiral conveyer F³, located just back of the harrow, levels the 80 earth, and the roller F⁴ smooths the surface. Motion is transmitted to the harrow from the main shaft by means of the belt F⁵, and to the conveyer F³ by means of the belted connection F⁶. The roller F⁴ is rotated by reason of frictional contact with the earth as the machine 85 moves forward.

Suitable mechanism will be provided whereby the machine may be adjusted or set to cut different depths; but as nothing new nor particularly novel is embraced a description of such mechanism is omitted.

Having thus described my invention, what I claim as new, and desire to secure by Letters Patent, is—

1. In a ditching-machine, the combination, with an excavating-wheel composed of a number of curved buckets, arranged as described, of a stationary tubular shaft or chamber around which said wheel is adapted to revolve, the top part or upper side of said shaft inclosed by said wheel being provided with an elongated opening corresponding to the open space at the base of each bucket, and through which the earth gravitates into the 115 tubular shaft from each bucket in regular order, as described.

2. The combination, with an excavating-wheel consisting of a number of curved buckets attached to a common hub, of a tubular shaft upon which the excavating-wheel is mounted, having a suitable opening in the upper side thereof, and a spiral conveyer arranged on the inside of said shaft and having a right and left pitch from a common center, 120 whereby the earth discharged from the buckets into the shaft is carried outward toward each end and deposited out of the way on each side of the ditch being excavated, substantially as described.

3. The combination, with a series of radially-arranged excavating-buckets, of the flange-disks A' A², the angular bearing-boxes a a', the bearing-collars a² a³, and the tubular

stationary shaft A³, substantially as and for the purpose described.

4. In a ditching-machine, the combination, with a track adapted to have an independent adjustment and movement relative to the supporting frame-work, of a rack-bar attached to said track, a pinion mounted on the inner end of the shaft C³ and adapted to engage with said rack-bar, a ratchet-wheel mounted on the opposite end of said shaft, a feed-dog pivoted to the rocking arm C⁵ and engaging with said ratchet-wheel, and the rod C⁶, having one end secured to the rocking arm and the opposite end having an eccentric connection with the main driving-shaft, whereby the machine is intermittently moved forward in the manner described.

5. In a ditching-machine, the combination, with a system of horizontally and vertically

arranged shafts having a series of bevel gear-wheels mounted on each of said shafts and adapted to engage with each other, of the track on which the machine is moved forward and the outside base-timbers, D² D³, whereby the weight of the machine proper may be alternately transferred from one to the other, substantially as and for the purpose set forth.

6. In a ditching-machine, the combination, with a rotating harrow, of a spiral conveyer located just back of said harrow and a roller located back of the conveyer, substantially as and for the purpose set forth.
